UNITED STATES PATENT OFFICE.

LOUIS WEILER, OF BAXTER, IOWA.

EGG-STAMPING DEVICE.

1,238,229.

Specification of Letters Patent. Patented Aug. 28, 1917.

Application filed April 5, 1916. Serial No. 89,085.

To all whom it may concern:

Be it known that I, LOUIS WEILER, a citizen of the United States, residing at Baxter, in the county of Jasper and State of

5 Iowa, have invented certain new and useful Improvements in Egg-Stamping Devices, of which the following is a specification.

The present invention relates to hand stamps and more particularly to new and 10 useful improvements in egg stamping devices.

An object of my invention is to provide an egg stamping device adapted to be 15 grasped in the hand of the user and engaged with the surface of an egg whereby to place a designating date or letter upon the egg.

Another object of my invention is to provide an egg stamping device of the class described provided with means for engagement 20 with three or more fingers of the hand of the user and having yieldable stamping means associated therewith for engagement with an egg, said stamping means being formed of rubber or similar flexible material whereby 25 to engage an egg without danger of breaking the latter. The finger engaging portions are so arranged on the device as to permit lifting of the egg from the place at which the same is stamped and depositing the same in 30 a box or package therefor.

A further object of my invention is to provide in an egg stamping device means for changing the date or designating letters associated with the stamping element.

35 Other objects and advantages to be derived from the use of my improved egg stamping device will appear from the following detail description and the claims, taken with an inspection of the accompanying drawing, in which—

Figure 1 is a perspective view of an egg stamping device embodying the improvements of my invention,

Fig. 2 is an end elevation of the egg stamping device, the user's hand being shown in dotted lines, and

Fig. 3 is a bottom plan view of the stamping element showing the manner of stamping the designating letters upon the date or 50 the like.

Referring more particularly to the drawing, wherein similar characters of reference designate like and corresponding parts throughout the various views, 1 designates 55 the main body portion of my improved egg stamping device and 2 the finger or hand

engaging member comprising a plurality of loops 3 fastened at their free ends to the body 1 by means of rivets 4 or the like.

The egg engaging or stamping portion of my invention is designated 5 and is formed 60 preferably of rubber or some similar flexible material, whereby when applied to an egg in stamping relation thereto the same will conform to the shape of the egg and at the same time depositing the stamping fluid 65 thereon in the shape of letters or similar characters.

I have shown one form of type carrying means for use in conjunction with my improved stamp, said type carrying means including a plurality of sections 6 having letters or similar indicia carried thereby forming the type. The sections 6 are mounted in a groove 8 extending longitudinally of the 75 portion 5. The groove 8 is best shown in Fig. 1 and is preferably dove-tailed in cross section of the section 6.

In order to cushion the egg stamping portion 5 I provide a plurality of coil spring 80 elements 9 connecting said portion 5 with the body 1. The springs 9 serve as shock absorbers and prevent fracturing the egg during a stamping operation. The coil spring elements 9 provides means for automatically 85 conforming the flexible member 5 to the configuration of the egg upon the application of the same.

The device is shown in use in Fig. 2, and it will be seen that the three fingers of the 90 user's hand, shown in dotted lines, are engaged through the loop 3. The egg stamping portion 5 is now placed on the egg, the flexible portion conforming to the egg convex surface. The springs 9 serve to absorb 95 any undue shock which otherwise might be imparted to the egg from the body 1. Continuing the impressions now on the egg the thumb and middle finger of the user's hand may be engaged with the egg. In this manner the egg may be lifted and placed in a 100 suitable container therefor and released, the operation being repeated for the next stamping of an egg.

From the above description taken in connection with the accompanying drawing, it is thought that a clear and comprehensive understanding of the construction, operation and advantages of my invention may be had, and while I have shown and described my 110 invention as embodying a specific structure, I desire that it be understood that I may

make such changes on said structure as do not depart from the spirit and scope of the invention as claimed.

What I claim as new and desire to secure by Letters-Patent is:—

In an egg stamping device, a rectangular rigid body portion, a flexible egg engaging section co-extensive with the body portion, coil springs, one end of the coil springs being secured to the body portion adjacent the

corners thereof, the other end of the coil springs being secured to the flexible egg engaging section adjacent the corners thereof, and finger engaging means rigidly secured to the body permitting the egg member to be retained in the desired position while stamping.

In testimony whereof I affix my signature hereto.

LOUIS WEILLER.
